UNITED STATES PATENT OFFICE.

LOUIS HILL, OF AKRON, OHIO.

WINDING-MECHANISM INDICATOR.

Application filed December 15, 1923. Serial No. 680,805.

My invention relates to winding mechanism indicators, and is suitable for use upon talking machines and analogous devices, in which a spring is wound by hand and in which it is desirable to constantly indicate the changing condition of the winding spring.

More particularly stated, my invention comprehends a winding mechanism indicator so constructed and arranged that the operator can ascertain at a glance to what extent the spring mechanism used for driving the machine has run down, the indication being registered practically in spring pressure as well as in the number of turns of the winding crank necessary to completely rewind the mechanism.

Reference is made to the accompanying drawing forming a part of this specification, and in which like reference characters indicate like parts throughout all of the figures.

Figure 1 is a fragmentary rear view, being partly an elevation and partly a section of a winding mechanism provided with my device and forming a part of a talking machine.

Figure 2 is a fragmentary plan, showing a portion of the mechanism appearing in Figure 1.

Figure 3 is a section on the line 3—3 of Figure 1, looking in the direction indicated by the arrows.

Figure 4 is a section on the line 4—4 of Figure 1, looking in the direction indicated by the arrows.

Figure 5 is a fragmentary elevation of a dial and pointer used for registering the indications.

Figure 6 is an inverted plan or bottom view of a worm wheel and parts immediately associated therewith appearing in Figures 1 and 3.

The inner surface of the front wall of a talking machine cabinet appears at 7, and at 45 8 is a base plate.

Extending upwardly from the base plate 8 is a metallic standard 9, provided with a foot 10, this foot being secured rigidly to the base board.

50 The standard 9 is provided with a bearing 11. Extending through this bearing and supported thereby is a shaft 12. Mounted rigidly upon the shaft 12 is the hand crank

13, used for winding the spring mechanism, in the usual manner.

55 The shaft 12 is provided with teeth 14, as indicated in Figure 2, and mounted adjacent these teeth is a pawl 15. A spring 16 presses the pawl against the teeth, so as to prevent retrograde rotation of the shaft. 60 The shaft carries a gear wheel 17, and this gear wheel engages a large gear 18 of annular form. The gear 18 is mounted upon and supported by a casing member 19, inside of which is the motor spring 19.

65 A shaft 20 carries the casing member 19, and extends through the same and also through another casing member 21, the latter carrying a large gear member 22 of annular form. The casing member 19 is revoluble relatively to the shaft 20, and the casing 21 is rigid relatively to this shaft, and thus revoluble therewith relatively to the base plate 8. The parts 19 to 22 inclusive, being old and well known, are here shown conventionally.

70 They are so arranged that when the crank 13 is turned by hand, in the manner well known in this art, the rotation of the gear wheel 17 causes positive rotation of the annular gear member 18 and casing member 19, thus winding the motor spring 19. This spring by its tension causes the casing member 21 and the annular gear member 22 to turn, in the same direction as the casing member 19 and the annular gear 75 member 18, so as to allow the spring to unwind slowly, as the driven mechanism is actuated.

80 Wheel 23^a is secured rigidly upon and revoluble with a flexible shaft 24, which extends through bearings 25, the latter being secured to the standard 9 by bolts 26.

85 The flexible shaft 24 is a single spring wire having the form of a solid cylinder, and extends axially through another flexible shaft 27, the latter having the form of a hollow cylinder, as may be understood from Figure 1.

90 The gear wheel 23 is secured rigidly upon and revoluble with a flexible shaft 27, which carries a pinion 28, and extends through a wearing sleeve 30, forming a part of a bearing 31. This bearing is secured upon the inner face of the cabinet wall 7 by means of screws 32.

100 A worm 33, having the general form of

105

a left handed screw, and another worm 34 having the form of a right handed screw, are each supported at one end by the bearing 31. For this purpose the worm 33 is provided with a smooth portion 35 and the worm 34 is similarly provided with a smooth portion 36. The portions 35 and 36 are essentially journal necks.

The worm 33 carries a pinion 37 whereby it is driven. This pinion engages the pinion 28, carried by the flexible shaft 27. The worm 34 is provided with a pinion 38 by which it is turned, this pinion engaging and being driven by a pinion 39, secured by means of a key 29 upon the flexible shaft 24, and thus revoluble with this shaft.

Two spindles 40 and 41 engage the adjacent ends of the worms 33 and 34, and thus serve as bearings for supporting the same. These two conical ended spindles are carried by a plate 42, the latter being secured by a screw 43 upon the cabinet wall. A worm wheel 44 of small size is located between the worms 33 and 34, and is constantly in engagement with them both. The worm wheel 44 carries and is spaced midway between a pair of guide wheels 45, each having the form of a disk, the worm wheel and the two guide wheels being mounted upon a short shaft 46. The worm wheel rolls bodily to the right or left according to Figure 1, the direction and extent of its rotation being controlled by movements of the worms 33 and 34, or by the individual movement of either one of these worms as the case may be, depending upon the condition of the mechanism, and this condition changes from time to time.

A rocking arm 47 is provided with a slot 48, as shown more particularly in Figure 1, the arm being so positioned that the shaft 46 extends through it at all times. The rocking arm 47 is provided with a sector 49 integral with it, and having the form shown in Figure 1. The rocking arm and sector 49 are mounted upon a shaft 50, serving as a pivot.

The sector 49 engages the pinion 51, mounted upon a shaft 52, this shaft extending through the cabinet wall and also through a dial 53, mounted upon the front face of the wall, as may be understood from Figure 6. The shaft 52 carries a pointer 54, so arranged that by the rocking of the shaft 52 back and forth, the point 54 is moved around over the face of the dial 53.

For the purpose of enabling the positions and movements of the pointer 54 relatively to the dial 53 to be easily observed and measured, I provide the dial 53 with numerals, as shown in Figure 6, the numerals in this particular instance ranging from 1 to 23 inclusive, and I further provide an index mark 55, in this instance having substantially a V-form, serving as a zero point, or

at least as a starting point from which all reckonings are easily made.

The parts are so proportioned and arranged that when the winding mechanism is completely run down to the limit allowed in practice, the worm wheel 44 occupies its extreme position to the left according to Figure 1; and when the winding mechanism is fully wound up, that is, to the maximum permitted in practice, the worm wheel 44 occupies its extreme position to the right according to this figure. In accordance with these movements of the worm wheel, and dependent thereupon, the pointer 54 registers a zero indication whenever the worm wheel 44 occupies its extreme position to the left according to Figure 1 as just described, and on the other hand registers a maximum indication whenever the worm wheel 44 reaches the limit of its travel to the right according to this figure.

The extreme movements just described for the pointer, and an infinite number of such other movements intermediate the extremes mentioned, may readily be traced by simply following out the co-relation of the various movable parts.

Suppose that the hand crank 13 is turned. Its rotation being clockwise, the shaft 12 and the gear wheel 17 must turn in the same direction. This causes the annular gear member 18 and casing member 19 to turn, in the direction indicated for them in Figure 1 by the arrow for this purpose. The gear wheel 23 is therefore turned in the reverse direction, and the flexible shaft 27 thereupon turns the pinion 28 in the same direction that the hand crank 13 is turning. The pinion 28 turns the pinion 37 and the worm shaft 33 in a counter clockwise direction, reckoning from the viewpoint of a person standing adjacent the hand crank 13 in Figure 1, and looking to the left according to this figure. The worm 33 continues to turn only so long as the hand crank 13 is being turned, and thus the rotation of the worm 33 stops abruptly at any instant whenever from any cause the operator stops turning the hand crank.

The rotation of the worm 33, as just described, turns the worm wheel 44 in a clockwise direction according to Figure 1. Hence, this worm gear must roll bodily to the right according to Figure 1.

Suppose, next, that the motor mechanism is completely wound, and is running. The shaft 12 and all parts driven thereby being now motionless; the worm 33 is stationary. However, the casing member 21 and the annular gear member 22 are moving in the direction indicated for these parts by an arrow shown for the purpose in Figure 1. The gear wheel 23 being driven in the reverse direction, the pinion 39 is of course turning in a clockwise direction and the pinion 38

in a counter clockwise direction, from the viewpoint of an observer standing near the hand crank 13. The counter-clockwise rotation of the worm 34, as just described, tends to carry the worm wheel 44 bodily to the left according to Figure 1.

Thus the rotation of the worm 34, incidental to the unwinding of the spring, is in the contrary direction to that of the rotation 10 of the worm 33, incidental to the winding of the motor spring. Another way of stating the same thing is, that when the worm 33 turns faster than the worm 44, as is always the case in practice whenever the 15 hand crank 15 is turned by hand in the usual manner, the worm wheel 44 rolls bodily to the right according to Figure 1, and the pointer 54 turns in a clockwise direction according to Figure 6. When, however, the 20 spring runs down the worm wheel 44 moves back to the left according to Figure 1, and as a consequence the pointer 54 turns in a counter-clockwise direction according to Figure 6 back to the zero point whence it 25 started.

The operation of my device may be readily understood from the foregoing description.

In practice, the operator glances at the dial mechanism shown in Figure 6, and thus 30 ascertains whether or not any winding of the motor spring is necessary, and if so about how many turns of the hand crank are needed. This done, he grasps the hand crank and turns it accordingly, keeping his eye on 35 the dial mechanism.

Again, if one phonographic record is finished and another one is about to be started, the operator by glancing at the dial mechanism can form an idea as to whether or not 40 the mechanism should be rewound before starting to play the new record.

I do not limit myself to the precise mechanism shown and described, as variations may be made therein without departing from my 45 invention, the scope of which is commensurate with my claims.

Having thus described my invention, what I claim as new and desire to secure by Letters Patent is as follows:

50 1. The combination of winding mechanism, a spring motor, driven mechanism connected with said spring motor and actuated thereby as the spring of said motor unwinds, a flexible shaft connected with said winding mechanism, another flexible shaft formed out of said driven mechanism, a pair of worms, one connected with the first mentioned shaft and driven thereby, the other connected with said second mentioned flexible shaft thereby driven, a worm wheel engaging both of said worms and revoluble under the joint control thereof, so that rotation of one of said flexible shafts moves said worm wheel in one direction and rotation of 60 the other of said flexible shaft moves said

worm wheel in the opposite direction, a rocking shaft connected with said worm wheel and movable back and forth as said worm wheel is moved back and forth, and indicator mechanism connected with said rocking 70 shaft and movable therewith.

2. The combination of winding mechanism, a spring motor, driven mechanism connected with said spring motor and actuated thereby as the spring of said motor unwinds, a flexible shaft connected with said winding mechanism and driven thereby, another flexible shaft formed out of said driven mechanism and actuated by movements of 75 said driven mechanism, a pointer movable in two directions, connections from said pointer to one of said flexible shafts for enabling said pointer to be driven in one direction of its travel, and connections from said pointer to the other of said shafts for enabling said 80 pointer to be driven in the opposite direction of its travel.

3. The combination of winding mechanism, a spring motor, driven mechanism connected with said spring motor and actuated 85 thereby, a flexible shaft connected with said winding mechanism and driven thereby so as to turn when said winding mechanism is being wound, another flexible shaft formed out of said driven mechanism and actuated 90 thereby so as to turn continuously while the spring of said motor unwinds, a worm connected with first mentioned flexible shaft and thereby driven in one direction of rotation, another worm connected with said sec-

95 ond mentioned flexible shaft and thereby driven in the same direction of rotation as that of first mentioned worm, a worm wheel 100 engaging both of said worms and movable bodily along the same in one direction when said winding mechanism is being wound and in the opposite direction when the spring of 105 said motor is being unwound, rocking mechanism connected with said worm wheel and movable back and forth by movements thereof, and a movable pointer connected with said rocking mechanism for registering indications.

4. The combination of winding mechanism, a spring motor, driven mechanism connected with said spring motor and actuated 110 thereby, a flexible shaft connected with said winding mechanism and driven thereby so as to turn when said winding mechanism is being wound, another flexible shaft formed out of said driven mechanism and actuated 115 thereby so as to turn continuously while the spring of said motor unwinds, a worm connected with first mentioned flexible shaft and thereby driven in one direction of rotation, another worm connected with said second mentioned flexible shaft and thereby driven in the same direction of rotation as that of first mentioned worm, a worm wheel 120 engaging both of said worms and movable 125

bodily along the same in one direction when said winding mechanism is being wound and in the opposite direction when the spring of said motor is unwinding, and mechanism 5 connected with said worm wheel and actuated thereby for registering indications as to the condition of the said spring motor.

5. The combination of a winding mechanism, a spring motor, driven mechanism connected by said spring motor and actuated thereby, a flexible shaft connected with said winding mechanism and driven by said winding mechanism, said flexible shaft being hollow, a second flexible shaft extending 10 through first mentioned shaft and formed out of said driven mechanism and actuated thereby, a pair of revoluble worm shafts connected with and driven by said flexible shafts so as to turn in the same direction, a 15 worm wheel engaging both of said worm shafts and movable bodily in the direction of the length thereof, one of said worm shafts tending to roll said worm wheel in one direction and the other of said worm 20 shafts tending to roll said worm wheel in the opposite direction, a rocking shaft connected with said worm wheel and adapted to be rocked by the movements of said worm 25

wheel lengthwise of said worm shafts, a movable pointer, and connections from said 30 rocking shaft to said pointer.

6. The combination of a winding mechanism, a spring motor, driven mechanism connected by said spring motor and actuated thereby, a flexible shaft connected with said 35 winding mechanism and driven by said winding mechanism, said flexible shaft being hollow, a second flexible shaft extending through first mentioned shaft and formed out of said driven mechanism and actuated 40 thereby, a pair of revoluble worm shafts connected with and driven by said flexible shafts so as to turn in the same direction, a worm wheel engaging both of said worm shafts and movable bodily in the direction of 45 the length thereof, one of said worm shafts tending to roll said worm wheel in one direction and the other of said worm shafts tending to roll said worm wheel in the opposite direction, and mechanism controllable 50 by said worm wheel for registering indications.

Signed at Akron, in the county of Summit and State of Ohio, this 13th day of December, 1923.

LOUIS HILL.
